UNITED STATES PATENT OFFICE.

JAMES SCHÖNBERG, OF NEW YORK, N. Y., ASSIGNOR OF ONE-HALF TO
EDWARD WESTON HUNT, OF SAME PLACE.

HATCHWAY COVERING OR DOOR.

SPECIFICATION forming part of Letters Patent No. 351,467, dated October 26, 1886.

Application filed December 2, 1885. Serial No. 184,524. (No model.)

To all whom it may concern:

Be it known that I, JAMES SCHÖNBERG, of the city, county, and State of New York, have invented a new and useful Improvement in 5 Hatchway Coverings or Doors; and I hereby declare the following to be a full and clear description thereof.

The object of this invention is to provide a covering or door for hatchway or similar openings in a floor or roof with such operative mechanism as will permit the door to be opened or closed by the proper manipulation of a single operating rope or cord, which may readily be conducted into the office of the building in 10 which these improved hatchway-coverings are in use, or to any other suitable station whence the same may be operated, and the mechanism is so constructed and arranged that a single rope or cord with suitable branch ropes attached 15 thereto can be made to operate all of the doors or covers for the several floors through which the hatchway extends.

Other peculiar features of this invention and of the details and essential characteristics 20 thereof will be hereinafter fully explained.

The invention will be readily understood by reference to the accompanying drawings, of which—

Figure 1 is a front sectional elevation of a 25 hatchway-opening extending up through the roof, and which is provided with these improved doors or coverings. Fig. 2 is a transverse sectional elevation of the same. Fig. 3 shows a modified form of the roof-door. Fig. 35 4 is a detailed front elevation of the sliding follower and its hinged connection with the door or covering-piece. Fig. 5 is a sectional transverse elevation of the said sliding follower and its hinged connection with the door.

40 The several floors or roof through which the hatchway is formed are each provided with a door or doors, A A', which are each connected with an operating cord or rope, G, by which they are drawn into an opened position or into a closed position, as the case may be, the said operating-rope acting to draw the door into either the one or the other position, according to its arrangement for the one purpose or the other, and then on releasing the 45 said operating-rope the door, by its own gravity or by the action of an added weight, is al-

lowed to return automatically to its other position.

The doors A, which are fitted to the floors of a building, differ only from the door A', 55 which is fitted to the roof, in this, that the floor-doors are made to move into a vertical position above their respective horizontal positions when they are opened, and below the horizontal position in the case of the roof-door, 60 of course modifying the operating mechanism only to such an extent as to produce these results.

The floor-door A, in its horizontal position, rests on ways a, which are fitted to and supported in the frame-work at the sides of the hatchway-opening. These way-pieces do not extend quite across the hatchway-opening, a small space, a', being left at one side of the hatchway-opening, at the ends of the said way-pieces, 70 for the purpose of allowing any dust or obstruction resting upon the top or working face of the said way-pieces to be pushed off by the door as it slides or runs along on the said ways.

The front corners of the door A are provided 75 with sheaves or rollers a², which rest on and roll along on the ways a when the said door is moved over or withdrawn from the hatchway-opening, thereby reducing the frictional resistance to the moving of the door laterally 80 on its said ways.

One edge of the door or cover A is hinged by a compound hinge, C C' C², to a sliding follower-piece, D, which moves vertically up and down in the ways E. The upper edge of the 85 said follower-piece D is hinged or jointed to the lower ends of a pair of diagonal locking-bars, F, made somewhat in the form of the letter V, and pivoted together at the point of their intersection by the pivot-pin f. The 90 upper ends of these locking-bars are connected by links or equivalent connections f' f² with the bottom part of another follower-piece, D', which also slides up and down in the ways E. The follower-pieces D and D' have anti-friction 95 rollers d in their ends or sides, which are guided by the said ways E, so as to diminish the frictional resistance at those points of contact. The upper end of the upper follower, D, has an operating cord or rope, G, attached 100 to it, and the said cord or rope, after passing up from the said follower and over suitable

sheaves or rollers, *g g*, is conducted down into the office of the building, or to any other desired station, where it can easily be operated or controlled by any authorized person, or 5 kept under such surveillance as is deemed desirable. Where two or more doors or covers are employed to protect a corresponding number of hatchways, suitable branch ropes are used to connect each door with the main line 10 or cord *G*. The mechanism of these parts *D F D'* is such, as is clearly shown in Fig. 4, that when the follower *D'* is raised up by its actuating-cord *G*, the links or attachments *f' f'* draw the two upper ends of the locking-bars *F* slightly toward each other and away 15 from their ways *E*; but when the follower *D'* and its attached locking-bars *F* drop down the upper ends of the said locking-bars fall outwardly from each other, and automatically drop into 20 notches *e e*, formed in the adjacent faces of the way-pieces *E* to receive them, and by engaging in the said notches *e e* the locking-bars *F*, pressing as their lower ends do on the follower-piece *D*, and through it on the door *A*, form an automatic lock for holding the hatchway-door 25 down, and thus acting as a burglar-proof lock for the said door, for it can only then be opened by raising the upper follower, *D'*, and the surreptitious raising of this can only be accomplished by gaining access to the operating-cord *G*, which (to provide against this contingency) is housed in or covered in some way (not shown) to prevent unauthorized manipulation. The door *A*, therefore, when closed, and 30 the cord *G* once slackened, is automatically locked closed by the locking-bars *F*. The front corners of the hatch-door, to render the locking complete, runs under clamping-plates *a³*, which hold the front edge of the said door 35 down when it is closed, so that it cannot be raised up.

The hinge by which the door *A* is attached to its follower-piece *D* is formed of three parts or leaves, *C C' C²*, which are joined and pivoted together, as shown in Figs. 4 and 5, so as to form a three-part hinge, the outer leaves, *C* and *C²*, of which fold in opposite directions upon the central part, *C'*, thus permitting the changes of position existing between the door 40 *A* and its operating-follower *D* as the door is placed in either its closed or its open position, as shown, respectively, in the full and the dotted lines of Fig. 2. This compound hinge readily combines the door *A* with the sliding follower *D* in such a manner as to render practical the relative positions of the said door and follower at the closed or horizontal position of the door, and also at the vertical or open position of the said door, in which last position 45 it is placed entirely outside of the hatchway-opening, as shown by the dotted lines in Fig. 2, thus leaving the entire opening clear, and it also accommodates itself and its attached door and follower to all the intermediate positions required between the said limits of its motion.

The upper door, *A'*, which is intended to

cover the hatchway-opening in the roof, which is frequently required, differs from the floor-door *A* only in this, that it is required to move down in opening, instead of up, as in the case of the floor-door, and of course with such adaptations of operating mechanism as required to produce this result. In this case the sheaves *a⁴*, on which the door rests on its ways *A²*, are placed in the central part of the door, so as to form a kind of central pivotal support on which the door is supported, and about which it partially rotates as it is moved from its vertical to its horizontal position, and vice versa. The ways *A²*, on which the door rests when it is in its closed position, slope downwardly toward the side at which the door opens, as shown in Figs. 2 and 3, and they may be either straight sloping bars attached at both 75 their ends, as in Fig. 3, or slightly curved and attached at only one of their ends, as in Fig. 2. Either of these forms of construction is considered the full equivalent of the other. The rear edge of the door *A'* is connected by 80 a hinge, *C C' C²*, to the sliding follower *D'*, which slides up and down in the before-mentioned ways *E*, and an attached cord, *G'*, is connected with it and operated in a manner similar to that above described for the cord *G*, 85 or it may be coupled with the said cord *G*. The closed and open positions of the door *A'* are respectively shown by the full and the dotted lines in Fig. 2. In case the door *A'* should have no roof or covering over it, it must be 90 made water-tight, and its closed position formed at such an angle of inclination as will be required to throw off the rain-water, and its edges covered with weather-strips *a⁵*.

In case the hatchway-openings are very wide, 105 the doors or coverings may be made in two parts or folds arranged to open at two sides of the hatchway, instead of only at one side, as herein shown and described.

Having described my invention, I claim— 110

1. A hatchway-door arranged to slide horizontally over a hatchway-opening by means of an operating-follower hinged to one of its sides, and provided with a locking-bar which automatically engages with a fixed support on 115 the closing of the door, so as to automatically lock the door as soon as it is closed.

2. The combination of two or more hatchway-doors with one operating-rope leading from them through a closed housing or tubing 120 into the office or other station from which the opening is alone controlled.

3. A vertically-sliding follower for operating a hatchway-door, consisting of two follower-bars, *D D'*, arranged to slide up and 125 down in suitable vertical ways, *E*, and coupled together by a pair of V-shaped links, *F*, pivoted together by the pin *f* at their intersection, and having short coupling-links *f' f'*, for connecting them to the upper follower-piece, *D'*, 130 so as to allow the upper ends of the link-pieces *F* to swing laterally outward as soon as they are released from tensional strain, thereby permitting their said upper ends to automatically

engage in the locking-notches *e* on the way-pieces *E*, substantially as shown and described.

4. A door, *A*, coupled by a compound double-acting hinge, *C C' C²*, to a vertically-sliding follower, *D*, so that the follower, by being moved up or down, may push or draw the said door into a horizontal position on suitable ways prepared to receive it in that position, or into a vertical position outside of its closed or horizontal position, substantially as described.

5. The compound hinge *C C' C²*, in combination with the sliding hinged door *A* and the operating-follower *D*, substantially as described.

JAMES SCHÖNBERG.
